[57] CLAIM

The ornamental design for a vacuum deposition apparatus, substantially as shown and described.

DESCRIPTION

FIG. 1 is a front and left side perspective view of my new vacuum deposition apparatus design with the unshown bottom being substantially plain and unornamented;

FIG. 2 is top plan view thereof;

FIG. 3 is a side elevational view thereof, taken from the right side of FIG. 1.

FIG. 4 is a rear elevational view thereof.
